Primary Examiner — Rhea Shields(74) *Attorney, Agent, or Firm* — Greer, Burns & Crain, Ltd**CLAIM**

The ornamental design for a collection container, as shown and described.

DESCRIPTION

FIG. 1 is a top front perspective view of the present collection container showing our new design;

FIG. 2 is a front elevational view thereof;

FIG. 3 is a rear elevational view thereof;

FIG. 4 is a first side elevational view of same;

FIG. 5 is an opposite side elevational view thereof;

FIG. 6 is a top plan view thereof; and,

FIG. 7 is a bottom plan view thereof.

In the drawings, the broken lines are for the purpose of illustrating portions of the collection container that form no part of the claimed design.

1 Claim, 5 Drawing Sheets(56)
